UNITED STATES PATENT OFFICE.

JOHN W. JONES, OF SALUBRIA, IDAHO.

DESIGN FOR A CAR-DOOR HINGE.

SPECIFICATION forming part of Design No. 32,031, dated December 26, 1899.

Application filed November 29, 1899. Serial No. 738,734. Term of patent 7 years.

To all whom it may concern:

Be it known that I, JOHN W. JONES, a citizen of the United States, residing at Salubria, in the county of Washington and State of Idaho, have invented and produced a certain new and original Design for Car-Door Hinges; and I do declare the following to be a full, clear, and exact description of the invention, such as will enable others skilled in the art to

10 which it appertains to make and use the same.

The invention relates to a new and original design for a car-door hinge; and it consists of a design of the configuration shown in the accompanying drawings, in which—

15 Figure 1 is a perspective view of the hinge, and Fig. 2 is an end view.

The leading feature of the design comprises a horizontally-disposed arm 1, from

which depends a vertically-disposed arm 2, terminating in a horizontally-disposed arm 3, which is parallel with the horizontally-disposed arm 1. These three arms are provided with rows of apertures 4. Projecting from the horizontally-disposed arm 1 is an arm 5, which extends vertically, as shown at 6, and terminates in a forked head 7.

What I claim is—

The design for a car-door hinge, as herein shown and described.

In testimony whereof I have hereunto set my hand in presence of two subscribing witnesses.

JOHN W. JONES.
